UNITED STATES PATENT OFFICE.

MAX MEYERSON, OF NEW YORK, N. Y.

FOLDING CARRIER.

Application filed March 16, 1921. Serial No. 452,643.

To all whom it may concern:

Be it known that I, MAX MEYERSON, a citizen of the United States, residing at New York, in the county of New York and State 5 of New York, have invented certain new and useful Improvements in Folding Carriers, of which the following is a specification.

This invention relates to a folding carrier, the same being in the nature of an improvement upon the structure shown and described in Patent No. 1,323,715, Dec. 2, 1919.

An object of the present improvement is to provide a box which will be at once of stronger construction and of less cost to 15 manufacture than the box disclosed in said patent.

A further object is to so design the box that it may be more easily and quickly manipulated into its distended and collapsed 20 positions.

A further object is to so design the top, bottom and intermediate sections of the box that they will more efficiently cooperate with each other and will provide a more pleasing 25 and attractive exterior appearance, both when the box is collapsed and when distended, than is possible with the structure disclosed in said patent.

A further object is to provide simple and 30 efficient means for holding the box, and particularly the intermediate section thereof, in distended condition.

A further object is to provide an improved form of hinge wherewith to pivotally connect together the several parts of the structure.

Other objects and aims of the invention, more or less specific than those referred to above, will be in part obvious and in part 40 pointed out in the course of the following description of the elements, combinations, arrangements of parts and applications of principles, constituting the invention, and the scope of protection contemplated will be 45 indicated in the appended claims.

In the accompanying drawings which are to be taken as a part of this specification, and in which I have shown merely a preferred form of embodiment of the invention:—

50 Figure 1 is a perspective view of a carrier constructed in accordance with this invention, the same being shown collapsed.

Figure 2 is a transverse sectional view taken substantially upon the plane of line 55 II of Fig. 1.

Figure 3 is a similar view to that shown in Fig. 2, but showing the box, or carrier, partly open.

Figure 4 is a diagrammatic view corresponding to the showing in Fig. 3, but the 60 carrier being here fully distended.

Figure 5 is a diagrammatic view in top plan showing the carrier fully distended and illustrating in dotted lines the intermediate section of the carrier as being partly collapsed.

Figure 6 is an enlarged detail top edge view of one end of the intermediate section of the carrier.

Figure 7 is an end elevational view of the 70 carrier, parts being broken away for the saving of space.

Figure 8 is a further enlarged detail sectional view illustrating the hinge construction employed.

Figure 9 is an elevational view of the part 75 seen in Fig. 8.

Figure 10 is a fragmentary elevational view corresponding to the lower central portion of Fig. 7, but illustrating a modification thereof, and

Figure 11 is a fragmentary detail view of the corner construction employed.

Referring to the drawings for describing in detail the several features disclosed therein, the reference character L indicates what has been above referred to as the bottom section of the carrier. The reference character G indicates the intermediate, or body, section. And the reference character H indicates the top, or cover, section.

The bottom section L is of tray shape, and includes a bottom wall 1 having upturned marginal flanges 2. At the corners suitable reinforcing corner irons 3 are provided.

The top, or cover, section H is similar in general contour to the shape of the bottom section and may also carry reinforcing corner irons 4.

The body section is made up of a rear wall 5, a front wall 6 and opposite end walls 7 and 8. The end walls are each made up of two sections, as 9 and 10, hinged together at a central point, as at 11. The 105 sections 9 are hinged to the rear wall 5, as at 12, and the sections 10 are hinged to the front wall 6, as at 13.

By this arrangement the front wall 6 may be moved toward or away from the 110

rear wall 5 by the simple expedient of bowing inwardly the sections of the end walls 8, as seen by the dotted lines in Fig. 5.

The sections 10 of the end walls are provided with extending portions 14 continuing beyond the pivots 11 and adapted when in distended condition to lap against the inner surface of the sections 9, and these portions 14 preferably carry adjustable clip devices 15 with which to detachably connect them against movement out of distended position. These clips may be pivotally connected with the extensions 14 as by means of pivot devices 16, and they may be swung about their pivots to bring the clip portions thereof into straddling position over the juxtaposed upper edges of the sections 9 and the extensions 14, as clearly illustrated. It will be apparent that when these clips are in the position shown in Figs. 6 and 7, then the side walls of the box are permanently held in distended condition. To move these walls to collapsed position it is simply necessary, however, to swing the clips 15 out of engagement with the sections 9.

Concerning the extensions 14, it is important to note that they are of a size to overlap substantially the entire inner surface of the sections 9 and that, therefore, they greatly reinforce said sections in withstanding excessive strains which may be placed against them either from within or without the box.

The rear wall 5 is hinged at its lower edge to the adjacent flange 2 of the base, or bottom, section L, as at 17, so that it may swing freely from the position Fig. 3 downwardly into the bottom section, as in Fig. 2, and vice versa. When in the position shown in Fig. 3 the body section may be readily distended and the top section placed thereon, as seen in Fig. 4. When the body section is folded into the bottom section then the top section may be placed directly on to the bottom section, as seen in Figs. 1 and 2.

In its distended position the front wall 6 of the body is intended to rest upon one or more special supporting elements, as 18, which are carried by the front flange 2 of the bottom section for this purpose, said supports serving to hold the bottom and body sections in their appointed positions relative to each other.

In order to provide for a better fit of the three main sections of the device, and for a better appearance, the flanges 2 of the bottom section are preferably inclined upwardly and inwardly, substantially as best seen in Figs. 1 to 4. By this means the upper edge portion of the flanges may be brought to a closer and more accurate fit against the adjacent outer surface portions of the body section, while at the same time

disposing the lower portions of said flanges in a plane sufficiently removed from said outer surfaces of the body so that said lower portions of the flanges will stand in substantially the same vertical planes as 70 the flanges of the top section thereby giving to the completed article a much more attractive appearance than would be possible were the flanges 2 made vertical. Furthermore, it has been found that the inclined 75 position of the flanges 2 renders it possible to make the flanges of the top section stand nearer to the adjacent walls of the intermediate section than if said flanges 2 were made vertical and yet be capable of readily 80 telescoping over said flanges 2. This is due to the very close fit of the upper edges of said flanges 2 against the outer surface of the body section.

As a simple expedient for moving the end 85 walls of the body section to distended position suitable pull straps, as 19, may be connected therewith and extended outwardly through suitable openings, as 20, provided for the purpose in the end flanges 2 of the 90 bottom section. The inner ends of these straps may be connected with the sections 10 in the end walls preferably directly at the point of the hinges 11 so that a pull upon said straps will operate to move the wall sections 9 and 10 into alignment. A very important feature embodied in this part of the device is illustrated in Fig. 7, and consists in connecting the inner ends of the straps 19 at points in a plane above the openings 100 20. As illustrated, the inner end of the strap 19 extends through an opening 21 provided in the wall section 10 which is in a plane above the opening 20. It will be apparent that thus a pull upon the outer end of the 105 strap will not only operate to draw the wall 10 in a direction against the adjacent flange 2 but will also operate to draw said wall downwardly toward the bottom wall of the box. The downward strain will serve to 110 hold the front wall 6 in proper association with the supporting devices 18 at the front of the bottom section.

The extreme inner end of the straps 19 may be rigidly fixed with the wall sections 115 10 in any suitable manner, as for instance by means of rivets, or the like, as 22.

If desired, instead of a single strap, a double strap or cord may be employed, as shown in the modification Fig. 10. In this 120 instance the wall section 10 is provided with two separate openings, as 23 and 24, and the adjacent flange 2 is also provided with two separate openings, as 25 and 26. The cord, as 27, extends inwardly through openings 125 25 and 23, forms a loop inside of the wall 10 and continues outwardly through openings 24 and 26. A very simple construction is thus provided in which the outer portions of the cord 27 may whenever desired be 130

looped, or tied, together, as indicated by the dotted lines 28, outside of the flange 2, thus completing an efficient bond between the flange 2 and the side wall of the box serving 5 to hold the body of the box in fully distended condition for as long a period as desired.

The hinges employed for connecting together the several parts of the device are 10 preferably of metal and extend continuously throughout the length of the hinged parts. This is particularly important with respect to the joints by which the parts of the intermediate, or body, section G are connected together since at these points the hinges constitute very strong and efficient vertical reinforcing elements greatly increasing the strength of the box in resisting crushing strains which may be applied upon the top 20 of the box. The hinges 11 at the centers of the end walls provide a much needed reinforcement for said walls in resisting strains applied thereto by the straps 19. Note in this particular that the lower ends of said 25 hinges extend quite to the point of attachment of the inner ends of the straps, and that the pulling strains from the straps, instead of being felt only at one point upon said end walls, is transmitted by said hinges 30 to remote portions of said walls.

The double thickness of wall material provided by the extensions 14 is also important in resisting and distributing these strains.

By making the hinge 17, connecting together the body and bottom sections, continuous from end to end of the box a uniform distribution of strains applied from one of said sections to the other is given, and at the same time the wall 5 of the body 40 section is held against buckling or warping.

The particular design of the hinges may take any desired form but consists preferably of pieces of sheet metal bent into U shape and disposed to straddle the edge portions of the wall material, the pieces connected with two adjacent wall parts being appropriately cut away, as at 29, so that they 45 may intermesh with each other in hinge formation, and so that a pivot rod, as 30, may 50 connect the two pieces together. As a simple means for rigidly connecting these pieces with the wall parts, said pieces preferably have their edge portions provided with a plurality of tangs, as 31, projecting laterally therefrom and disposed so that they 55 extend through the wall material, the ends of the tangs being clinched over into and upon the opposite surface of the wall material to prevent detachment, as seen in Fig. 8. The 60 operation of mounting the hinges in this manner requires no rivets or other separate parts, and may thus be performed very quickly and economically. At the same time the material of the hinges, particularly the extreme 65 edge portions thereof, is made to lie closely

against the surface of the wall material. A smoother exterior surface is thus provided than if rivets were employed.

These hinges are of substantially the same design as the hinges shown and described in 70 my pending application Serial No. 451,204, except that in said pending application the rivets are employed as the fastening means.

When the box is in its collapsed condition, as seen in Fig. 1, the straps 19 may be connected together over the top surfaces of the 75 cover section to hold the parts assembled. When the box is distended the straps may extend upwardly along the sides of the end walls and thence be connected over the top 80 surface of the cover to hold the top firmly in covering position.

As seen by Fig. 11, and by the fragmental sectional view appearing in Fig. 7, the ends of the hinge 17 may be rigidly connected 85 with the adjacent corner irons 3, as by means of rivets 32, and with the corner hinges 12, as by means of rivets 33. Also the corner irons 3 referred to, may be cut away, as at 34, to accommodate the adjacent ends of the hinges 90 and yet leave a very strong and substantial portion, as 35, of said irons projecting upwardly for the support and protection of the adjacent portions of the end flanges 2 of the bottom section. 95

One of the purposes for which this box may be used is that of carrying small dogs, or other animals, and for this purpose it is contemplated that either or all of the walls of the intermediate or body section of the 100 box shall be provided with openings covered with wire gauze or the like, as 36, to the end that a free circulation of air may be had within the box.

While the wall members described may be 105 constructed of any suitable material, yet they preferably are formed of thin sheet card board or fibre board which may be varnished, or otherwise finished, on one, or both, its surfaces so as to produce an attractive 110 appearance.

As many changes could be made in this construction without departing from the scope of the invention as defined in the following claims, it is intended that all matter 115 contained in the above description or shown in the accompanying drawings, shall be interpreted as illustrative only and not in a limiting sense.

Having thus described my invention, what 120 I claim as new and desire to secure by Letters Patent is:—

1. A folding carrier comprising a bottom section in the form of a tray, a collapsible body section pivotally connected to swing 125 into and out of said tray, and a cover section adapted to fit either on to the body section when the body section is distended or on to the bottom section when the body section is folded down, the bottom section having side 130

wall parts over which the cover section is adapted to telescope, and said side wall parts being shaped so that the lower portions thereof stand substantially in the vertical 5 planes of the telescoping portions of the cover section, substantially as set forth.

2. A folding carrier comprising a bottom section in the form of a tray, a collapsible body section pivotally connected to swing 10 into and out of said tray when in its collapsed condition and adapted when in its distended condition to provide walls extending upwardly from the marginal walls of the tray, and a cover section, said marginal walls 15 of the tray being inclined upwardly and inwardly so that the upper edges thereof may lie snugly against the distended walls of the body section.

3. A folding carrier comprising a bottom 20 section, a collapsible body section made up of front, rear and end walls, means pivotally connecting the rear wall with the bottom section, each of said end walls comprising a pair of sections pivotally connected together 25 and to said front and rear walls whereby to enable movement of the front wall toward the rear wall for facilitating collapse, and means carried by one section of each of the end walls adapted to engage the other section 30 respectively operable to retain said end walls in distended condition.

4. A folding carrier comprising a bottom section, a collapsible body section made up of front, rear and end walls, means pivotally 35 connecting the rear wall with the bottom section, each of said end walls comprising a pair of sections pivotally connected together and to said front and rear walls whereby to enable movement of the front wall toward 40 the rear wall for facilitating collapse, one section of each of said end walls having an extension part continuing therefrom lapping the other section, and retaining means disposed to interengage between said lapping 45 portions for retaining said end walls in distended condition.

5. A folding carrier comprising a bottom section, a collapsible body section made up of front, rear and end walls, means pivotally 50 connecting the rear wall with the bottom section, each of said end walls comprising a pair of sections pivotally connected together and to said front and rear walls whereby to enable movement of the front 55 wall toward the rear wall for facilitating collapse, one section of each of said end walls having an extension part continuing therefrom lapping the other section, and a pair of manually operable latch devices carried 60 one by each of said extension parts operable to latch said extension parts with the adjacent other wall sections respectively.

6. A folding carrier comprising a bottom section, a collapsible body section made up 65 of front, rear and end walls, means pivotally

connecting the rear wall with the bottom section, each of said end walls comprising a pair of sections pivotally connected together and to said front and rear walls whereby to enable movement of the front 70 wall toward the rear wall for facilitating collapse, straps, one connected to each of said end walls and extending outwardly through openings formed in the bottom section adapted when drawn outwardly to hold the 75 end wall sections in distended condition, and the points of attachment of the straps with said end walls being in a plane above the openings in the bottom section through which the straps extend for the purpose set 80 forth.

7. A folding carrier comprising a bottom section, a collapsible body section made up of front, rear and end walls, means pivotally 85 connecting the rear wall with the bottom section, each of said end walls comprising a pair of sections pivotally connected together and to said front and rear walls whereby to enable movement of the front wall toward the rear wall for facilitating collapse, straps, one connected to each of said 90 end walls and extending outwardly through openings formed in the bottom section adapted when drawn outwardly to hold the end wall sections in distended condition, said 95 straps being connected with the end walls by being looped through two openings formed in said end walls, and there being two openings in the bottom section for each strap through which the two end portions of the strap extend, substantially as, and for the purpose set forth.

8. A folding carrier comprising a bottom section, a collapsible body section made up of front, rear and end walls, means pivotally 100 connecting the rear wall with the bottom section, each of said end walls comprising a pair of sections pivotally connected together and to said front and rear walls whereby to enable movement of the front 105 wall toward the rear wall for facilitating collapse, straps, one connected to each of said end walls and extending outwardly through openings formed in the bottom section adapted when drawn outwardly to hold the 110 end wall sections in distended condition, and said intermediate hinges having parts disposed adjacent to the points of attachment of the inner ends of said straps and having other portions continuing therefrom constituting means to reinforce the end walls in 115 sustaining the pull of said straps.

9. A folding carrier comprising a bottom section, a collapsible body section made up of front, rear and end walls, means pivotally 120 connecting the rear wall with the bottom section, a supporting element carried by the bottom section upon which the front wall of the body is intended to be supported, each end wall of the body comprising a pair of 125

sections pivotally connected together and to the front and rear walls whereby to facilitate collapse of the body, and means extending from the body in a direction downwardly of a character to connect the body with the bottom and to hold the end wall sections in distended condition and also to draw the body downwardly so as to retain the front wall of the body in engagement 10 with said supporting element.

10. A folding carrier comprising a bottom section in the form of a tray having a bottom wall and marginal walls, a collapsible body section adapted when in non-collapsed 15 condition to provide walls extending upwardly from and within the marginal walls of the bottom section and when in collapsed condition to be received within the bottom

section, and a cover section in the form of an inverted tray having a top wall and marginal walls adapted to telescope on to the body section when the body section is distended or on to the bottom section when the body section is collapsed, the bottom wall of the bottom section and the top wall of the 25 top section being of substantially equal size and the marginal walls of the bottom section being inclined upwardly and inwardly to facilitate telescopic placement thereonto of the top section when the body is collapsed. 30

In testimony whereof I affix my signature in the presence of two witnesses.

MAX MEYERSON.
